ADJUSTABLE FIXTURE HANGER

Marcus Bodian, Los Angeles, Calif., assignor to Sunbeam Lighting Company, Los Angeles, Calif., a firm

Application June 17, 1957, Serial No. 666,128

2 Claims. (Cl. 248—228)

This invention relates to an adjustable hanger for the attachment of fixtures such as light fixtures to ceilings.

One object of the invention is to provide an adjustable hanger which may be positioned on a channel member of a structural support for a ceiling, and which may also be easily adjusted vertically to correspond to any desired elevation relative to the ceiling. Another object is to provide a fixture hanger which may be attached to a channel structural member after the structural member is in place and attached to other members. A further object is to provide a fixture hanger which may be attached to ceiling support members with a minimum amount of labor.

These and other objects are attained by my invention which will be understood from the following description, reference being made to the accompanying drawings in which:

Fig. 1 is a side elevational view showing fixtures as attached to parallel channel structural members of the ceiling support;

Fig. 2 is a side elevational view of the fixture hanger; Fig. 3 is an elevational view partly in section taken in the direction of lines 3—3 of Fig. 2; and

Fig. 4 is a top elevational view partly in section showing the hanger from the position 4—4 of Fig. 3.

Referring to the drawings, the invention in its preferred form consists of a hanging bar 11 which consists of a formed sheet metal channel 12 having a back web 13 and having teeth 14 disposed in parallel relation on the two opposite flanges 15 of the channel, these teeth 14 being formed by notches 16 cut or otherwise formed in the flanges, the upper outer corner of each tooth 14 being tapered to facilitate the upward adjusting movement of the hanging bar, as will be described below. The hanging bar 11 at its lower end has means for the attachment of a lighting fixture, for example as shown, the threaded nipple 18.

The hanging bar 11 is arranged to be vertically movable in rectangular aligned slots 21 in the opposite sides 22 of a U-shaped locking strap 23 which consists of a U-shaped formed metal stamping whose legs or sides 22 are spaced a distance apart corresponding to the height of a horizontal structural channel member 25 of the ceiling structure. The sides 22 of the locking strap 23 are provided with flanges 26 turned inwardly toward each other, these being arranged to engage the web 27 of said structural channel member 25. The connecting member 28 of the U-shaped locking strap 23 is provided with a clamping screw means 30 mounted in a threaded hole 31 midway between the connected sides 22. The rectangular slots 21 in the sides 22 of the U-shaped locking strap 23 are disposed toward the clamping screw means 30, and said slots are of such width that the notched hanging bar 11 may be moved freely therein when the flanges 26 are engaged around the structural channel member 25. The notched hanging bar 11 is positioned relative to the flanges 32 of the structural channel member by selected pairs of teeth 14 of the hanging bar which rest upon said flanges, the corresponding notches 16 of the hanging bar 11 being pressed into this position by the clamping screw 30. In moving the hanging bar upwardly, the tapered upper corner edge 17

2

of the teeth 14 permits the easier positioning of the bar 11.

In the preferred structure the opening between the ends of the flanges 26 of the locking strap is large enough, and the length of the sides 22 is great enough, so that the locking strap may be placed over the structural channel member 27 without the necessity of spreading apart the sides 22, as shown in Fig. 3, although this latter expedient of spreading the sides may be used where the flanges are too long to permit the simple sliding of the locking strap over the channel, as shown.

Upon releasing the clamping screw 30 and permitting the hanging bar to slide freely in the slots 21, the elevation of the attaching means, for example, the threaded nipple 18 as shown, can be adjusted to suit the requirements of the particular job, both as to the thickness of the ceiling itself or the positioning of the attached fixture below the ceiling. The attaching means is not limited to a threaded nipple, but may be a stud or bolt, and the hanger may be employed equally well for holding temporary partitions, pipes or for similar purposes.

The advantages of my invention will be readily understood. The hanger may be adjusted laterally to any position on the structural channel members prior to the installation of the ceiling surface and is then readily adjustable up and down to fit the particular job by simply releasing the clamping screw 30 and tightening it again against the hanging bar to position the notches of said bar at any desired elevation.

30 I claim:

1. An adjustable fixture hanger adapted for attachment to an edge-positioned channel structural member of a ceiling support comprising a notched hanging bar having a plurality of rectangular notches spaced to engage a horizontal flange of said structural channel member; a U-shaped locking strap having inwardly turned flanges on the ends of the legs thereof, said flanges being adapted for slidably engaging the vertically disposed web face of said structural channel member, the legs of said strap being provided with aligned openings, said notched hanging bar being slidably mounted in said openings; and a positioning means on said locking strap for removably holding said bar at a selected notch against a flange edge of said channel member, said hanging bar having means at its lower end for attaching a fixture thereto.

2. An adjustable fixture hanger adapted for attachment to an edge-positioned channel structural member of a ceiling support comprising a notched hanging channel bar having a plurality of rectangular notches in both flanges spaced apart to form teeth to engage the horizontal flanges of said structural channel member; a U-shaped locking strap having inwardly turned flanges on the legs thereof, said flanges being adapted for slidably engaging the vertically disposed web face of said structural channel member, the legs of said strap being provided with aligned openings, said notched hanging channel bar being slidably mounted in said openings, and said openings being large enough to permit said hanging bar to freely slide therethrough; and a positioning screw means threaded into a threaded hole in the closed end of said U-shaped locking strap, said screw means being adapted for removably positioning said bar on the flange edges of said channel member, in a selected pair of notches in said bar, said hanging bar having means at its lower end for attaching a fixture thereto.
